UNIVERSAL MOUNTING FOR ROAD
MACHINE MOLD BOARDS

Henry C. French, Elm Grove, Wis., assignor to
The Heil Co., Milwaukee, Wis., a corporation of
Wisconsin

Application December 20, 1943, Serial No. 514,950

7 Claims. (Cl. 37—144)

1

This invention relates to improvements in universal mountings for road machine mold boards.

Certain types of road machines, such as trailbuilders, have their blade-carrying mold boards arranged for universal movement. Due to the massive nature of the parts and the necessity for unusual strength and rigidity, as well as accessibility for repairs, replacements and adjustments, the matter of providing an effective universal mounting for a mold board or blade presents a problem which has been effectively taken care of in the present invention by a commercially practical structure.

A further object of the invention is to provide a universal mounting for a road machine mold board which includes an A-frame formed of a pair of complementary, identical interchangeable arms which permits knock down of the unit for shipment and storage and a resulting saving in space and bulk.

A further object of the invention is to provide a universal mounting for a road machine mold board which embodies easily manufactured sturdy elements susceptible of simple assembly or disassembly.

A further object of the invention is to provide a universal mounting for a road machine mold board which is of very simple construction, which is highly efficient in operation, which is strong and durable, which is relatively inexpensive, and which is well adapted for the purposes described.

With the above and other objects in view the invention consists of the improved universal mounting for road machine mold boards, and its parts and combinations as set forth in the claims, and all equivalents thereof.

In the accompanying drawings in which the same reference characters indicate the same parts in all of the views:

Fig. 1 is a perspective view of a trailbuilder equipped with the improved universal mounting for its mold board;

Fig. 2 is an enlarged, fragmentary plan view of the forward portion of a trailbuilder provided with the improved universal mounting for its mold board, a portion being broken away and in section;

Fig. 3 is a fragmentary, rear perspective view of a road machine mold board showing a pivot bracket in detached relation thereto;

Fig. 4 is a fragmentary perspective view of a trailbuilder mold board and the complete universal mounting between it and the companion A-frame arms of the trailbuilder; and

Fig. 5 is an enlarged detail sectional view taken on line 5—5 of Fig. 2.

Referring now more particularly to the drawings it will appear that a certain type of road machine, known as a trailbuilder, is designated generally by the numeral 8. In so far as the

present invention is concerned it will not be necessary to refer to the details of construction of the trailbuilder. Suffice it to say that it is equipped with a forwardly projecting A-frame 9 whose inner ends are pivotally mounted on side mounting brackets 10 with pivotal movement of the A-frame in a vertical plane being effected and controlled by a cable system 11.

The invention has to do particularly with the universal mounting for a front mold board 12, the latter carrying or having its lower longitudinal edge formed as a cutting blade 13. In addition to the swinging movement imparted to the mold board and cutting blade through the pivotal mounting of the A-frame, whereby the blade may be raised and lowered relative to the ground being worked over, the mold board is susceptible of universal movements or adjustments relative to the A-frame 9.

The A-frame 9 is composed of a pair of complementary and interchangeable arms 14. The forward end of each arm rigidly carries on its top and bottom faces projecting spaced apart plates 15. When the arms 14 are in assembled relation to provide an integral A-frame, the forward ends of the arms 14 have their respective top and bottom plates 15 in lapping relationship, as best shown in Fig. 4, being connected together and to another element later to be described, by a vertical pivot bolt 16.

The rear face of the mold board 12, intermediate the ends thereof, is formed with a plate portion 17 having upper and lower flanges 18, which flanges are formed with arcuate grooves 19 described on a radius emanating from a recess 20 which is located in the plate portion 15 midway between the flanges 18.

Adapted for cooperation with the plate portion 17 is a pivot bracket 21 which includes a pivot plate 22, corresponding in size and shape to the plate portion 17 and having curved upper and lower edges corresponding to the curvature of the grooves 19. The outer face of the pivot plate 22 has welded thereto a massive block 23, having therethrough a vertical bore 24 to receive the previously mentioned pivot bolt 16. Extending forwardly from the inner face of the pivot plate 22 and centrally located with respect thereto, is a pivot stud 25 adapted to be received within the opening 20 in the mold board plate portion 17.

Prior to assembly of the mold board mounting elements, the arms 14, constituting the A-frame 9, may be disconnected, and for shipping and storage they may be disposed very compactly, occupying considerably less space than if the A-frame were an integral structure. The divided construction of the A-frame also makes for ease in disassembling the mold board carrying structure for convenience in repairs, adjustments and replacements. Likewise the pivot

bracket 21 is readily removable from the assembly. When the parts are to be assembled the pivot bracket 21 is held adjacent the mold board plate portion 17 in a position at right angles to that shown in Fig. 3. However, the pivot stud 25 is engaged in the aperture 20 and then the entire pivot bracket is turned through an arc so as to engage the curved extremities of the pivot plate 22 within the arcuate recesses 19, as shown in Figs. 4 and 5. Thereafter the forward ends of the A-frame arms 14 are brought together with their flanged plates 15 in lapping relationship and also disposed so as to embrace opposite ends of the block 23 of the pivot bracket. Registration of the apertures in the arm plates or tongues should be effected and the same are also brought into registration with the vertical bore 24 in the block 23, whereupon the pivot bolt 16 is inserted to join all of the parts.

With the mold board 12 then mounted as above described, it is obvious that the mold board may be turned or swung on the pivot bracket-carried stud 25. The curved grooves 19 permit this movement relative to the pivot plate 22 which is stationary. The movement described permits angular adjustments of the mold board in a vertical plane and transversely of the road or surface being worked on.

In addition to the pivotal movement just described, the mold board may be swung in a horizontal plane with the mold board and pivot bracket turning on the vertical pivot bolt 16. During these movements or adjustments, extension arms 26, whose inner ends are slidably or telescopically mounted on the side horizontal portions of the A-frame 9, may move compensatingly along said A-frame portion. The forward ends of the extension arms 26 are pivotally connected to rear side portions of the mold board 12, as shown in Figs. 1 and 2.

From the foregoing description it will be seen that the improved universal mounting for road machine mold boards is of very simple construction, possesses great strength and durability, permits ready assembly and disassembly of the parts, and provides for efficient universal movements of the mold board relative to the mold board mounting elements. The universal mounting is, furthermore, of practical and novel construction and is well adapted for the purposes described.

What is claimed as the invention is:

1. In a road machine, a pair of angled, complementary, interchangeable arms disposed with their forward ends in abutment across the front of the machine to form a frame and having rearwardly extended portions pivotally mounted on the machine on horizontal axes, a pivot bracket interposed between the abutting forward ends of said arms, a vertically disposed pivot bolt connecting said portions of the arms together and to the pivot bracket, a mold board, and a detachable connection effecting a pivotal mounting on a horizontal axis between the pivot bracket and an intermediate portion of the mold board.

2. In a road machine, a pair of complementary, separable arms disposed with their forward ends in abutment across the front of the machine to form a frame and having rearwardly extending portions pivotally mounted on the machine on horizontal axes, clevis means on the abutting ends of said arms, an independent, removable pivot bracket, a vertically disposed pivot member connecting a portion of said bracket to said clevis means, a mold board having recesses on its inner

face intermediate the ends thereof, and means on said pivot bracket removably engaging said mold board recesses and effecting a pivotal connection on a horizontal axis.

3. In a road machine, a yoke-like frame including separable side arm portions pivotally mounted on the machine on horizontal axes and having their front portions extending across the front of the machine and meeting in abutting relationship, clevis means on said abutting frame arm portions, an independent, detachable pivot bracket including a bored block and a plate, a vertically disposed pivot bolt removably extended through said clevis means and the bore of said block, a mold board having recesses on its inner face intermediate the ends thereof, and projecting means on said pivot bracket plate removably engaging said mold board recesses and effecting a pivotal connection on a horizontal axis.

4. In a road machine, a pair of angled, complementary interchangeable arms having their forward ends formed as clevises and in mutual lapping engagement, said arms forming a frame whose forward portion is disposed across the front of the machine and whose rearwardly disposed portions are pivotally mounted on the machine on horizontal axes, a pivot bracket including a bored block and a plate, a pair of opposite edge portions of the plate being curved, a pivot member extended through the clevis portions of the arms and the bore of said block, a mold board having an intermediate portion of its inner face formed with spaced upper and lower shelves having curved recesses therein and a socket between the shelves, the recesses in the shelves and the curved edges of the bracket plate all being described on a radius emanating from said socket, and a pivot stud on said bracket plate removably engaging said mold board socket on an axis at right angles to the axis of the block carried pivot member, said curved edges of said bracket plate being adjustably and removably engaged in said recessed shelves.

5. In a bulldozer, the combination of: a supporting frame; a blade, having a socket on the rear face thereof; an attaching member, a portion of which when properly oriented being capable of insertion in the socket, and when otherwise oriented being incapable of removal therefrom but being capable of swivel motion therein, and another portion of which when in the second above-mentioned orientation being capable of hinge connection with the supporting frame; and means for effecting such hinge connection.

6. In a bulldozer, the combination of: a U-shaped supporting frame; a blade, having one member of a combined bayonet joint and swivel connection on the center of the rear face thereof; an attaching means comprising the other member of the bayonet connection; and a vertical pivot hinge connection between the attaching means and the frame.

7. In a bulldozer, the combination of: a U-shaped supporting frame; a blade, having the female member of a combined bayonet joint and swivel connection on the center of the rear face thereof; an attaching means comprising the male member of the bayonet connection; and a vertical pivot hinge connection between the attaching means and the frame.
